 signors to E. I. du Pont de Nemours & Company,
 Wilmington, Del., a corporation of Delaware

Application August 30, 1939, Serial No. 292,590

3 Claims. (CL. 102—7)

The present invention relates to the art of electric blasting initiators.

This application is a continuation-in-part of our copending application, Serial Number 181,647, filed December 24, 1937, and contains matter divided out of said copending application.

The electric blasting initiators known to the art have been characterized by several outstanding defects. They have not been completely impervious to water and/or moisture, especially under storage conditions and other rigorous conditions imposed in the field. Consequently these initiator structures of the prior art have not been sufficiently durable to withstand the physical 10 wear encountered in the field, including forces tending to pull the leg wires out of the cap, such as severe tamping and the like. Furthermore their lack of resistance to abrasion, especially at the locus of the entrance of the leg wires into 15 the mouth of the shell, has been recognized as productive of many difficulties including short circuits, accidental firing, misfires, and the like.

The object of the present invention is the production of a new and improved electric blasting 20 initiator. A further object is an electric blasting initiator so constructed that the leg wires are firmly gripped to resist forces which would otherwise tend to pull them out of the initiator. An additional object is an electric blasting initiator 25 of enhanced water resistance. Another object is such an initiator with improved abrasion resistance at the locus of the emergence of the leg wires from the mouth of the shell.

We have determined that the foregoing objects 30 are accomplished and disadvantages overcome by constructing an electric blasting initiator comprising leg wires provided with thermoplastic insulation, a composition plug of rubber-like material vulcanized about said leg wires to form a 35 water impervious seal at the interface between said thermoplastic insulation and said rubber-like composition plug, and a loaded shell crimped about said rubber-like plug in water impervious 40 relationship therewith.

Our invention may be understood more readily 45 by referring to the accompanying drawing which serves to illustrate a preferred embodiment of the invention, but should not be construed to limit the scope thereof. Like numerals designate 50 corresponding parts throughout the several figures.

Referring generally to the various figures of the drawing, Figure 1 is a view in cross-section of the improved electric blasting initiator of our invention. Figure 2 is an enlarged view of the

rubber-like plug formed about the leg wires bearing plastic insulation. Figure 3 is a similar view wherein the plug takes a different form. Fig. 4 is a bottom end view of the modification shown in Fig. 3.

Referring in greater detail to the various figures, in Figure 1 the numeral 1 designates a metal shell into which the plug 2, formed about the leg wires 3, is crimped in water impervious relationship at 4. These leg wires 3 are provided with durable plastic insulation 5, preferably comprising an ethyl cellulose composition. This insulation preferably terminates within the body of the plug, as shown at locus 6. The rubber-like plug material is molded and/or vulcanized about both 10 the exposed and insulated portions of the wires to form a water impervious juncture at the interface between plug and insulation. This operation may be carried out by any molding process. We prefer to employ the pressure molding process 15 described and claimed in our copending application, Serial Number 181,647, filed December 24, 1937, from which much of the subject matter of the present application was derived, pursuant to 20 a requirement for division.

We have described our plug material as "rubber-like." By this term we refer to those properties generally possessed by natural and synthetic rubber compositions and the like, namely, elasticity, springiness, extensibility, and in one 25 sense of the word, compressibility. This capacity of our plug material for rebounding, springing back and returning to its original shape without permanent deformation, which is characteristic 30 of natural and synthetic rubber and similar compositions, is effective in this electric blasting initiator of our invention for the purpose of forming a water impermeable closure between the shell and plug by crimping the shell of the blasting initiator into the rubber-like plug material. It 35 is understood, therefore, that we intend to include within the scope of our invention any of the many recognized materials composing these rubber-like properties, whenever a plug of the same is formed about electric blasting initiator 40 leg wires provided with plastic insulation.

In the foregoing we have expressed a preference for thermoplastic insulation comprising an ethyl cellulose composition. It should be understood that our invention includes as well, compositions comprising cellulose ethers generally, and including toughening agents, conventional plasticising agents and the like, compositions comprising cellulose derivatives except nitrocelulose, compositions comprising, respectively, 45 50 55

polyvinyl acetals, methacrylic acid derivatives, polythene compositions, and similar durable plastic and/or thermoplastic materials. This material preferably is disposed about the conductor as a solid sheath, extruded sheaths being preferred.

The electric blasting initiator product of our invention possesses several outstanding advantages. The combination of the rubber-like plug molded about the thermoplastic insulation produces an electric blasting initiator of enhanced water resistance due to the effective juncture of the plug material with the insulation as a result of the vulcanizing and/or molding process in which the plug is formed. Furthermore, remarkably improved abrasion resistance results at the locus in which the leg wires emerge from the plug at the mouth of the shell, perhaps due to the slight, temporary give in the plug when pressure is exercised on the leg wires and due in particular to the effective seal between plug material and plastic insulation on said wires. Furthermore, because of the effective seal of plug material to plastic insulation, the leg wires are firmly gripped in the shell to resist forces otherwise tending to pull them out of the initiator, such as those forces encountered in tamping operations and the like. This initiator completely solves the waterproofing problem for electric blasting initiators, a problem which has been a continual source of complaint for many years. In the conventional types when a column of waterproofing material was poured over the bridge plug and allowed to solidify within the cap shell, the results were never satisfactory. At summer temperatures the material tended to soften, flow past the plug, and desensitize the cap charges. At very low temperatures, also, the seal was none too tight. In addition to the waterproofing composition it was necessary to superpose a sulfur composition. The rubber-like plug has eliminated these two sealing compositions and has insured water tightness. Furthermore it permits the use of a considerably shorter cap shell. This is particularly desirable in the case of delay initiators, where the length is very considerable in those of the higher delay periods. Our assembly gives an improved waterproof product over that wherein cotton yarn is employed as insulation on the leg wires, especially in view of the fact that the strands of yarn tend to form a wick through a rubber plug or any other type of plug and decrease the waterproof quality of the assembly. Furthermore the thermoplastic insulation, such as ethyl cellulose compositions or the like, possesses a resistance to abrasion greater than that of the commonly used insulation coatings, and accordingly the initiator assembly will stand more abuse, generally, without impairment of function. Furthermore this insulation presents an improved appearance and allows ready differentiation between different types of electric wires and between the two leg wires by the use of variously colored pigments. For instance, we have found it to be advantageous to employ

an assembly wherein insulation of one leg wire contains a yellow pigment and the insulation of the other contains a red pigment. However, any conceivable contrasting colors may be employed. This permits the miner or blaster to tell at a 5 glance which wire he is dealing with at any point throughout its length without tracing the same back to any other point. This is especially advantageous in operations in which leg wires of unusual length are employed. We find that product to be especially desirable which is prepared by the process of our copending application, Serial Number 181,647, filed December 24, 1937. As a result of this process the plastic insulation is joined to the rubber-like plug in the step of 15 vulcanizing the plug in place without impairment of the insulation at any point and without any harmful effect on the insulation from the vulcanizing heat, as disclosed and claimed in said copending application. This result is accomplished by the step of maintaining the thermoplastic insulation in a solid state, preferably by conducting heat away from the same at the time the rubber-like plug is molded about said insulation. 20

In the foregoing we have described the preferred embodiments of our invention. It will be understood, however, that many variations may be made without departing from the scope of the invention. We intend to be limited, therefore, 25 only by the following patent claims.

We claim:

1. An electric blasting initiator comprising a loaded shell, spaced leg wires provided with insulation comprising a thermoplastic material 35 entering the mouth of said shell, a plug of rubber-like material of the character described formed about said spaced leg wires and disposed in a position closing the mouth of said shell, and a crimp extending around the circumference of said 40 shell in the region enclosing said plug forcing the shell wall into and deforming said rubber-like plug to complete a water impervious juncture.

2. The electric blasting initiator of claim 1 wherein the thermoplastic insulation comprises a 45 cellulose ether composition.

3. In an electric blasting initiator including a loaded shell, the closure elements comprising leg wires provided with insulation comprising a thermoplastic material, a plug of rubber-like material of the character described formed about 50 said leg wires and in contact with said thermoplastic insulation substantially in the absence of the intermingling of said thermoplastic insulation with said rubber-like composition, said wires and plug being disposed in a position closing the mouth of said shell, and a crimp extending around the circumference of said shell in the region enclosing said plug forcing the shell wall into and deforming said rubber-like plug to complete a 55 water impervious juncture.
